(57) **CLAIM**

The ornamental design for a continuous positive airway pres-
sure device, as shown and described.

DESCRIPTION

FIG. 1 is a front, top, left perspective view of a first embodiment of a continuous positive airway pressure device showing our new design;

FIG. 2 is a left side elevation view of the continuous positive airway pressure device of FIG. 1, the right side view being a mirror image thereof;

FIG. 3 is a front elevation view of the continuous positive airway pressure device of FIG. 1;

FIG. 4 is a rear elevation view of the continuous positive airway pressure device of FIG. 1;

FIG. 5 is a top plan view of the continuous positive airway pressure device of FIG. 1;

FIG. 6 is a bottom plan view of the continuous positive airway pressure device of FIG. 1; and,

FIG. 7 is a front, top, left perspective view of a second embodiment of a translucent body of the continuous positive airway pressure device of FIGS. 1-6, it being understood that all other surfaces are the same as those of the first embodiment.

The broken lines showing portions of the design in all figures are included for the purpose of illustrating environment and unclaimed features and forms not part of the claimed design.
